Attorney.

UNITED STATES PATENT OFFICE.

ALBERT D. LANEVILLE, OF MANCHESTER, NEW HAMPSHIRE.

PISTON FOR ENGINES.

1,368,167.

Specification of Letters Patent.

Patented Feb. 8, 1921.

Application filed November 1, 1919. Serial No. 334,936.

To all whom it may concern:

Be it known that I, ALBERT D. LANEVILLE, a citizen of the United States, and a resident of Manchester, in the county of Hillsborough and State of New Hampshire, have invented certain new and useful Improvements in Pistons for Engines, of which the following is a full, clear, and exact specification.

10 In the majority of makes of internal combustion engines employed for the propulsion of automobiles and the like, it is a laborious and tedious job to remove the pistons therefrom for the purpose of renewing the packing rings. The object of this invention is the effecting of means whereby the packing rings may be renewed without thus removing the pistons and disconnecting many parts difficult to reach and manipulate.

To this end I provide each piston with an easily removed portion in which the piston rings are carried, so that by simply unbolted the cylinder head member and taking out a couple of screws, such portion can be readily removed, the packing rings removed and reground, or fresh ones substituted therefor.

30 In the drawings forming part of this specification, Figure 1 is a longitudinal section through the line 3-3 in Fig. 3. Fig. 2 is a side view of the piston showing immediately above it the removable portion in section. Fig. 3 is a plan view of the removable portion. Fig. 4 is a plan view of the piston without the removable portion. Fig. 5 is a detail sectional view showing the screw-locking device. Fig. 6 is a view of the same from a different angle.

40 For the sake of brevity, I will call the removable portion of the piston a "cap". The main body of the piston is of well known construction, being of the bucket type, having the pitman 1 pivotally connected thereto by a pin 2. This piston body 3 is formed with a closed neck 4, having a shoulder 5, the neck being somewhat smaller in diameter than the interior of the cap 6, while the exterior diameters of the cap and piston are 50 alike.

In the periphery of the cap are the annular grooves 7 receiving the packing rings 9, which are of well known form and removable from the grooves 7 in the usual manner 55 when the cap is outside of the engine cylinder.

For fastening the cap 6 upon the piston 3, I prefer to form the interior of the cap with lugs 10, and the exterior of the neck 4 with corresponding lugs 11, the latter lugs 60 being provided with stop-extensions 12. By slipping the cap down about the neck, which is readily done when the lugs 10 and out of alignment with the lugs 11, and then giving the cap a partial rotation sufficient to 65 bring the lugs 10 beneath the lugs 11, no direct pull can withdraw the cap from the piston. For insuring tightness, the lugs 10 and 11 are given slightly slanting coacting surfaces 13. Should this coaction prove insufficient, the stop-extensions 12 will prevent the cap from being turned so far as to disengage the lugs.

To hold the cap so that it cannot turn while in use and thereby free itself from the 75 piston, I prefer to provide one or more bolts 14 tapped into the neck and passing through the flat surface or top 15 of the cap, as shown in Figs. 1 and 3. For preventing these screws or bolts 14 from working out, a small 80 hole 16 is drilled into the cap at each side of a bolt head, and a piece of spring wire 17 sprung into them in the slot 19 of the bolt head, as shown in Figs. 5 and 6. A small notch 20 in one edge of a slot 19 enables the 85 wire 17 to be pried out and the bolts to be unscrewed.

Thus constructed, the cap 6 can be easily removed from the piston without disturbing either the latter or any of its connections, 90 and as easily returned thereto after the change in packing rings.

To insure a gas-tight fit between the cap and piston, the edge of the cap is formed with an annular projection 21 fitting in a 95 corresponding groove 22 having a gasket 24 therein, as shown in Fig. 1.

What I claim is:

1. A piston having a neck at its upper end, a cupped member, said piston neck and 100 cupped member having coacting lugs for enabling them to be turned into firm engagement, removable means for locking said neck and member against accidental release, and packing means carried by said cupped 105 member.

2. A piston having a neck at its upper end, a cupped member, said neck and member having coacting lugs for enabling them to be turned into firm engagement, a bolt 110 passing through the top portion of said member and screwing into said neck, said

- bolt having a slotted countersunk head, means removably engaging said slot for locking the bolt against accidental turning, and packing means carried by said member.
- 5 3. A piston having a neck at its upper end, a cupped member equal to the piston in diameter, packing means carried by said member, said neck and member having co-acting projections for enabling them to be turned into firm engagement, a bolt passing through the top portion of said member and screwing into said neck, the head of said bolt being slotted and countersunk, and a length of spring wire lying in said slot and terminally held in recesses formed in the 15 said top portion.
4. A piston having a neck and a shoulder, the shoulder having an annular groove therein, a cup equal in diameter to the piston and having an annular projection fitting said 20 groove, a gasket in said groove, means for locking said cup and piston firmly together, and packing means carried by said cup.
- In testimony that I claim the foregoing invention, I have hereunto set my hand this 25 27th day of October, 1919.

ALBERT D. LANEVILLE.
